Inventor:
W. U. Bohm.

UNITED STATES PATENT OFFICE.

WILLIAM U. BOHM, OF SAN FRANCISCO, CALIFORNIA.

BUCKLE FOR WAIST-BELTS.

Specification forming part of Letters Patent No. 37,489, dated January 27, 1863.

To all whom it may concern:

Be it known that I, WILLIAM U. BOHM, of the city and county of San Francisco, State of California, have invented a new and useful improvement in the manufacture of buckles for ladies' waist-belts, and all other belts used with buckles; and I do hereby declare that the following is a full, clear, and exact description of the construction and operation of the same, reference being had to the drawings and to the letters of reference marked thereon.

The improvement consists in the construction of the buckles, as follows: A rim is used as usual for buckles. A clasp, C, is placed in the center of the rim formed as an ornament or plain, which turns on a joint. On the back of the clasp is placed three or more prongs, as D D D. In Fig. 1 or 3 said clasp or ornament is furnished with a snap or bolt worked by a spring, so as to prevent the clasp from being accidentally opened, as E in Fig. 2 or 3, with a bar to turn, as A in Fig. 1. Underneath the clasp C is placed a cross-piece, G, reaching from one side of the open space in the rim to the other, which leads the belt when pushed through the buckle. A bar, Fig. 4, is constructed on back of the rim, which crosses it from one end to the other. Right in the center underneath the cross-piece G on said bar, Fig. 4, the belt is secured. The bar, Fig. 4, is furnished with a button, H, so as to keep the belt on its place, also with three holes,

fff, for the prongs D D D to pass through into the bar. By buckling, the clasp C is opened, as in Fig. 1, and the loose end of the belt will be slid through between the bar, Fig. 4, and the cross-piece G; then when closing the clasp C the prongs D D D will pass through the belt right into the bar, Fig. 4, and both ends of the belt will be secured. The clasp C is also made to open from either end or side of the buckle, according to choice, as is seen in Fig. 3, which opens endwise.

The drawings will more fully and in detail explain the improvement for which a patent is desired.

What I claim therefore as my invention and improvement, and desire to secure by Letters Patent, is—

The entire machinery of the buckle, (with the exception of the rim,) as set forth in the foregoing specification, together with the application and use of said machinery to the purposes set forth in the petition and specification.

In witness whereof I have hereunto subscribed my name, at the city of San Francisco, State of California, this 7th day of October, 1862.

W. U. BOHM.

In presence of—

F. W. CRAIG,
P. B. CORNWALL.
